UNITED STATES PATENT OFFICE.

EDWARD J. NOBLE, OF NEW YORK, N. Y.

SPARK-PLUG.

1,110,813.

Specification of Letters Patent. Patented Sept. 15, 1914.

Application filed October 5, 1912. Serial No. 724,028.

To all whom it may concern:

Be it known that I, EDWARD J. NOBLE, a citizen of the United States, residing at New York, in the county of New York and State 5 of New York, have invented certain new and useful Improvements in Spark-Plugs, of which the following is a specification.

This invention relates to spark plugs for internal combustion engines and the like, 10 and its novelty consists in the construction and adaptation of the parts. In the operation of engines of this character, the spark plugs employed to ignite the charge of compressed gas deteriorate in quality by reason 15 of the fact that the conductivity of the sparking terminals is lessened because of a deposit of carbon thereon due to the imperfect combustion of the gases within the cylinder of the engine and the insulating efficiency 20 of the insulating materials employed to insulate the sparking elements from each other is likewise impaired by a similar deposit of carbon. The purpose of my invention 25 is to overcome the difficulties arising from this situation and to provide a simple means by which the sparking terminals or the insulating material interposed between them may be cleansed of such deposit of 30 carbon without removing them from the engines in which they are used, and in a simple and expeditious manner.

In the drawings, Figure 1 is a central longitudinal section of a spark plug embodying my invention; Fig. 2 is a detail of the upper portion of such a plug, and Fig. 3 is a detail of the lower portion of the rotating rod and wiping arms; Fig. 4 is a bottom plan view of the device shown in Fig. 1; Fig. 5 is a central longitudinal section of a spark plug embodying a slightly modified form of my invention; Fig. 6 is a bottom plan view thereof; Fig. 7 is an elevation of a second modified form of the spark plug embodying my invention; Fig. 45 8 is a central longitudinal section thereof; Fig. 9 is a bottom plan view thereof; Fig. 10 is a bottom plan view of the sparking terminals; and Fig. 11 is a detail of the wiping basket.

Referring to the construction shown in Figs. 1, 2, 3 and 4, 20 is a bushing adapted to be inserted into an aperture in the head

of an engine and it is threaded externally for that purpose. It is provided with a limiting flange 22 and with polygonal surfaces 23 to facilitate its rotation by means of a wrench or other suitable tool. At its lower extremity it is provided with a sparking terminal indicated at 24. Located within the bushing 20 is a tubular casing 25 made of suitable insulating material, preferably mica or porcelain. Inside of this casing is a tube 26 of conducting material, preferably steel. It is provided with an annular flange 27 adapted to fit snugly within an annular recess formed in the casing 25 to receive it, and at its opposite end it is externally threaded at 28 to engage the internal threads of a collar 30 made of suitable conducting material, for instance, brass 70 or steel, and which is adapted to fit over the end of the tube 26 and beyond the casing 25. The tube 26 is provided with an outwardly projecting sparking terminal indicated at 29. Projecting from the collar is an ordinary binding post 31 to which a suitable electric conductor (not shown) may be attached.

Arranged within the tube 26 is a cylindrical rod 33 having a squared portion 34 at its upper end. A disk 35, having a squared central aperture adapted to fit over the squared portion 34 of the rod 33 and to be rotated with it, is placed above the collar 30. At its lower end, the rod 33 is provided with one or more radially projecting wiping arms 36 which are turned upward at their extremities.

A lock nut 37 is adapted to fit over the casing 25 within the bushing 20, the bushing being internally threaded for a portion of its length to receive such lock nut which is externally threaded to engage therewith.

Means are provided to position the rod 33 and its wiping arms 36 as follows: The disk 35 is provided with a cam tooth 40 on its lower edge, and the collar 30 is provided with a recess 41 on its upper edge adapted to receive this cam tooth (see Fig. 2). When the tooth 40 is engaged in the recess 41, the wiping arms 36 are farthest away from the sparking terminals 24 and 29, and these arms are then in their normal position. A coiled spring 42 adapted to impinge

against a disk 43 rigidly secured to or made integral with the rod 33, and also to impinge against the upper portion of the disk 35, tends to hold the disk 35 under constant tension against the collar 30 so as to insure the engagement of the tooth 40 with the recess 41 whenever the parts are in position to permit it.

When the rod 33 is rotated, as it may be 10 by the application of a suitable tool to its squared upper portion, the wiping arms 36 at its opposite extremity, as such rotation continues, pass between the sparking terminals 24 and 29 and, being of such a size and 15 shape that they contact with the surfaces of both of these terminals, they wipe such terminals clean and remove any deposit which may have adhered thereto, and leave them in a proper conducting condition. 20 The operator knows when such wiping contact has taken place by means of the position of the tooth 40 with respect to the recess 41 at any time. It is readily understood that by the rotation of this central rod 33, the 25 sparking terminals may be cleansed as often as may be desired without removing the spark plug from the cylinder to which it is attached and without impairing its conductivity or efficiency. 30 As one of the things to be guarded against in the use of a spark plug is any leakage of gas from the inside of the cylinder, and as this gas is heated and under great pressure, I provide means for preventing such leakage even although the central rod 33 is rotatable within the tube 26 comprising a disk 360 secured to or made integral with the lower end of the rod 33, and which disk fits snugly against the lower extremity of the 40 tube 26, and in fact is pressed upwardly against such extremity by the pressure of the gases in the cylinder and which forms an effectual seal preventing the escape of such gases through the very small surface 45 between the rotatable rod 33 and its inclosing tube, should such escape become otherwise possible.

In Figs. 5 and 6, there is illustrated a modified form of the device. In these figures as before, 20 is the bushing engaging the engine cylinder aperture and it is provided with the limiting flange 22 and the polygonal surfaces 23 to facilitate its rotation. At its lower extremity, it is provided 55 with the sparking terminal 24 which, however, is turned inwardly at its lower extremity as is shown in Fig. 5. Located within the bushing 20 is the tubular casing 25 made of suitable insulating material, 60 preferably mica or porcelain as before, but at its lower end it is provided with a restriction or recess 250 and with a terminal conical foot 251. Inside of this casing is the tube 26 with its annular flange 27 which,

however, is adapted to fit snugly against the 65 lower portion of the foot 251 of the casing 25 and which extends beneath such casing. At its opposite end this tube 26 is externally threaded at 28 to engage the internal threads 70 of the collar 30 which, as before, is adapted to fit over the end of the tube 26 and beyond the casing 25. The tube 26 is also provided with an outwardly projecting sparking terminal 29 as before. Projecting from the collar 30 is the binding post 31. 75

Arranged within the tube 26 in this construction is the cylindrical rod 33 having the squared portion 34, and there is also the same construction of the disk 35 with its squared central aperture adapted to fit over 80 the squared portion 34 of the rod, and to be rotated with it. At its lower end this rod 33 is, however, not provided with the radial projecting wiping arms 36 shown in Figs. 1 and 3, but is provided with a device which I 85 call for convenience a wiping basket comprising a ring 331 adapted to encircle the restricted portion 250 of the casing 25 to be supported thereon, and comprising also downwardly projecting arms 332 which are 90 in close contact to the sloping sides of the foot 251 of the casing 25 and which at their lower extremities are secured to or made integral with the sealing disk 360 which forms the lower terminus for the rod 33. 95

The sparking terminals 24 and 29 in this construction are so placed that when the rod 33 is rotated as before, the downwardly projecting rods 332 of the wiping basket wipes against the foot 251 of the casing 25 and 100 passes between the ends of the two sparking terminals and cleanses and wipes them as in the construction first described.

The means for rotating the rod 33 and positioning it with respect to the sparking terminals, namely, the disk 35 provided with its cam tooth 40 and the recess 41 in the collar 30, and the intermediate spring 42, are the same as in the construction shown in Figs. 1 and 4, as is also the lock nut 37. 105

In Figs. 7, 8, 9, 10 and 11, there is shown a still further modification of the device embodying the invention, in which the parts are the same as those illustrated in Figs. 5 and 6 with the exception of the positive electrode 290, which in this case is secured to or made integral with the sealing disk 360 which forms the bottom of the wiping basket and which, therefore, rotates with it when the cylindrical rod 33 is rotated, and, by the 115 contact of this electrode in the course of its rotation with the other sparking terminal 24, effectually cleans the contacting surfaces of these sparking terminals and removes any carbon deposit thereon. In other words, 120 the wiping basket is provided to cleanse the lower foot 251 of the tubular casing 25, and the positive electrode 290 secured to and ro-

tating with this basket serves as a wiping arm to cleanse the contacting surfaces of the sparking electrodes.

What I claim is:

5. 1. A spark plug, having a sparking terminal, a cleaning device for the terminal rotatably mounted on the plug and movable into and out of contact with the terminal, and means for locking the cleaning device to 10 the plug against accidental rotation, said means engaging the cleaning device to secure it only when the same is out of contact with the sparking terminal.
2. A spark plug, having a sparking terminal, a cleaning device for the terminal rotatably mounted on the plug and movable into and out of contact with the terminal, and means for locking the cleaning device against accidental rotation, said means comprising 15 detachably interlocking parts carried respectively by the plug and cleaning device and interlocking only when the cleaning device is out of contact with the sparking terminal.
25. 3. A spark plug having a sparking terminal at its inner end, a cleaning device comprising a shaft rotatably mounted in the plug and projecting from both ends thereof, a cleaning finger mounted on the inner end 30 of the shaft and movable therewith into and out of contact with the terminal, and detachably interlocking devices carried by the outer end of the plug and shaft for securing 35 said shaft against rotation, said devices interlocking only when the cleaning finger is out of contact with the terminal.
4. A spark plug having a sparking terminal at its inner end, a cleaning device comprising a shaft rotatably mounted in the 40 plug and projecting from both ends thereof, a cleaning finger mounted on the inner end of the shaft and movable therewith into and out of contact with the terminal, and a spring-pressed device longitudinally slidably 45 upon the outer end of the shaft and having a detachable interlocking engagement with the plug for holding the shaft against rotation.
5. A spark plug having a sparking terminal, a cleaning device comprising a shaft rotatably mounted in the plug and projecting from both ends thereof, a cleaning finger mounted on the inner end of the shaft and operating on the terminal, the outer portion 55 of the shaft being angular in cross section, a disk slidably mounted on the angular portion of the shaft and detachably interlocking with the outer end of the plug, another disk mounted on said shaft in spaced relation to 60 the first mentioned disk, and a spring interposed between the disks.
6. A plug, comprising a casing having a 65 sparking terminal projecting beyond its inner end, a tubular conductor in the casing having its inner end projecting beyond the casing and provided with a latterally projecting terminal coating with the first mentioned terminal and spaced therefrom, a shaft rotatably mounted in the tubular conductor and projecting beyond the same, and a cleaning finger carried by the projecting end of the shaft and having an upstanding end that operates between the terminals on the rotation of the shaft.
7. A spark plug comprising a casing 70 adapted to be inserted in the engine cylinder, a sparking terminal connected thereto, an electrical conductor suitably insulated from said casing and a sparking terminal connected thereto, a device adapted to be rotated between the two sparking terminals to clean them, means for positioning such device consisting of a mutually engageable tooth and notch, one on a fixed portion of the spark plug and the other on the rotatable 80 device, and means for keeping the positioning means under tension as the rotatable device is moved.
8. A plug having a sparking terminal, an actuating device rotatably and reciprocably 85 mounted on the plug, a cleaning device for the sparking terminal carried by the actuating device and sweeping said terminal upon the rotation of the actuating device, and a plug-cleaning device mounted on the 90 terminal cleaning device and connected thereby to the actuating device, said plug cleaning device sweeping the exposed external portion of the plug upon the reciprocation of the actuating device.
9. A plug having a sparking terminal, an actuating device movably mounted on the 95 plug, a plurality of cleaning devices carried by the actuating device and successively sweeping the sparking terminal, and a plug 100 cleaning ring surrounding a portion of the plug and carried by the terminal cleaning devices, said ring being thereby connected to the actuating device.
10. A plug comprising a tubular casing, 105 an insulator located therein and projecting from the inner end thereof, said projecting portion having an annular external recess in its periphery, a reciprocatory actuating rod extending through the insulator, a cleaning 110 ring that normally surrounds the recess in spaced relation to the insulator and is movable over the end portion of the insulator, and a finger connecting the rod and the ring.
11. A spark plug having an inwardly projecting sparking terminal, and an insulator that has an end projecting inwardly from the plug, a cleaning device movably mounted on the plug and co-operating with the sparking terminal, and a cleaning ring carried by 115 the cleaning device and surrounding the projecting end of the insulator.
12. A spark plug comprising a casing hav-

ing an inwardly extending sparking terminal, an insulator located in the casing and projecting beyond the inner end of the same, a tubular conductor arranged within the insulator and having a sparking terminal on its inner end, a rotatable shaft located in the conductor, a finger carried by the inner end of the shaft and operating between the sparking terminals, and a cleaning ring carried by the finger and surrounding the projecting

end of the insulator, said shaft having a longitudinal movement to effect a cleaning action of the ring upon the insulator.

In testimony whereof I affix my signature in presence of two witnesses.

EDWARD J. NOBLE.
